Primary Examiner — Eric L Goodman*Assistant Examiner* — Amy C Wierenga(74) *Attorney, Agent, or Firm* — Polsinelli PC(57) **CLAIM**

I claim the ornamental design for a mould for a skimmer box lid, as shown and described.

DESCRIPTION

FIG. 1 is a top perspective view of a first embodiment of a mould for a skimmer box lid, showing my new design;

FIG. 2 is a bottom perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and

FIG. 8 is a rear elevational view thereof.

FIG. 9 is a top perspective view of a second embodiment of a mould for a skimmer box lid, showing my new design;

FIG. 10 is a bottom perspective view thereof;

FIG. 11 is a top plan view thereof; and,

FIG. 12 is a bottom plan view thereof.

The left side, right side, top plan, and bottom plan views of the second embodiment are omitted as they are the same as the left side, right side, top plan, and bottom plan views of the first embodiment.
